UNITED STATES PATENT OFFICE.

FORD W. HARRIS, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,158,492.

Specification of Letters Patent. Patented Nov. 2, 1915.

Application filed June 17, 1910. Serial No. 567,485.

To all whom it may concern:

Be it known that I, FORD W. HARRIS, a citizen of the United States, and a resident of Wilkinsburg, in the county of Allegheny and State of Pennsylvania, have invented 5 a new and useful Improvement in Circuit-Interrupters, of which the following is a specification.

My invention relates to electric circuit 10 interrupters of the oil-immersed type and it has special reference to interrupters which are required to handle comparatively large amounts of current at relatively low voltages.

15 The object of my invention is to provide a device, of the character above indicated, that shall be simple and durable in construction and adapted to perform its functions effectively.

20 In service of the above mentioned character, circuit breakers are subjected to particularly severe operating conditions, and the heating of the breaker parts is a matter of serious difficulty. The circuit breaker of 25 my invention is especially adapted to meet those requirements and to reduce excessive heating to a minimum, and it embodies means for securing intimate contact over the entire faces of the contact members, and for 30 insuring proper alinement of said members. Means are employed to eliminate the heating effect of eddy currents in the heavy copper terminals and additional means are provided for overcoming the destructive action 35 of the arcs which are formed when the circuit is interrupted.

In the accompanying drawings, Figure 1 is a view, partially in side elevation and 40 partially in section, of a circuit interrupter constructed in accordance with my invention. Fig. 2 is an end view, partially in section, and Fig. 3 is a diagrammatic view showing the circuit connections and the relations of the contact members.

45 Referring to the drawings, a circuit interrupter 1 comprises a frame 2 secured, at one end, to an insulating slab or panel 3 and supported, at the other end, by a pipe standard 4. Secured to the frame 2, is an insulating 50 slab or plate 5, to which are connected stationary contact terminals 6, 7, 8, 9, 10 and 11, arranged in pairs to coöperate with a plurality of movable bridging contact members 12, 13 and 14. The stationary contact 55 terminals are all alike and each of them is

fastened to the insulating plate 5 by means of bolts 18 and 19. Each of the terminals is grooved in such manner as to receive parallel copper straps 20, which fit tightly into the grooves and are held in place by pins 60 21. The multi-strap conductors 20 extend through rectangular openings 22 in the insulating plate 5 to form the terminals of the interrupter to which the external circuit connections are made. By constructing the 65 terminals in this manner, the eddy currents usually set up by heavy circuit currents are largely broken up and the consequent heating obviated.

The movable contact members 12, 13 and 70 14 are of like construction and are respectively adapted to engage the stationary contact terminals 6 to 11, inclusive, in pairs. Each movable member comprises a bridging member 23 and auxiliary arcing contact devices 24. The bridging member 23 is composed of strips of copper which are held together by means of curved clamping plates 26 and 27. Tubular member 30 of each arcing contact device may be integral 75 80 with the outer clamping plate 27 and may serve as a guide for arcing tip 31 which fits loosely therein. The arcing tip 31 rests against a helical spring 35 which surrounds a rod 36, the latter forming an arcing tip 85 extension to which a flexible copper shunt 37 is connected.

A contact plate 38 is secured to each main stationary contact terminal by means of a screw 39 and has its contact face slightly 90 inclined with reference to the direction of movement of the contact members, so that a slight rubbing action occurs as the contact surfaces come into engagement, thus insuring a perfect contact. 95

The movable contact members are pivotally suspended from rods 41 and 42 by means of pins 43 which are insulated from the current-carrying members of the interrupter by bushings 44. Rods 41 and 42 project through holes in the plate 5 and are provided with adjustable nuts 48 and 49, between which and a supporting member 45 are located helical springs 46 and 47 which surround the rods and carry the weight of 100 105 the contact members. The springs 46 and 47 may be independently adjusted by means of the adjusting nuts 48 and 49, to distribute the pressure uniformly across the faces of the contact member, and simultaneous action 110

of the contact members is insured by the supporting member 45, to which all of said members are connected.

It will be readily understood that the pin connection 43 between the operating mechanism and the movable contact members permits said members to automatically seat themselves and equalize the pressure between the contact surfaces. Furthermore, the yielding method of support gives a uniform distribution of pressure across the brush faces, so that very efficient electrical contact is obtained which obviates the excessive heating which is caused by poor contact of the coöperating members.

The supporting member 45 is suspended from a main lever 54, one end of which is pivotally supported by a stationary pin 55, and the other end of which is pivotally fastened to a yoke 52 having depending links 50 and 51 which are attached to the member 45.

The circuit interrupter is actuated by means of a compound operating lever 60, which is provided with an insulating handle 61 and comprises outer members 62 and an inner member 63. One end of a link 64 is connected to the lever 54 at 68 and its other end is connected to the inner member 63 of the operating lever at 69. The inner member 63 of the operating lever is fulcrumed on a pin 70 between the outer members 62 of said lever. The construction of the inner member 63 is such that a toggle formed by it and the connecting link 64, is drawn nearly into dead center when the operating lever is in its lowest position. The movement of the inner member 63 is independent of the outer members 62, except as the said members are secured together by a latch 73. The latch 73 is pivotally mounted at 74 between the members 62 and its lower portion forms a tripping lever 57 which is adapted to be struck by the hammer rod 92 of the movable core 91 of a tripping magnet 90, whenever said magnet is energized a predetermined amount. Pin 58 engages a spur 59 on the latch 73 and restricts movement of the latch in a counter clockwise direction. The handle 61 is provided with a recess to receive a rod 81 and a spring 80 which is interposed between a push button 82 on the rod, and the bottom of the recess. A locking trigger 83, which is normally adapted to engage a catch 86 on the operating handle to hold it in its "set" position, is pivoted at 84 on a bracket 88 and is maintained in engagement with the catch 86 by means of a spring 85 acting through a lever 60 arm 89. To release the locking trigger 83 from the operating handle, the rod 81 is forced inward against the spring 80, by means of the push button 82.

In order to absorb the shock occasioned by the sudden drop of the breaker parts as

the breaker opens, members 95 and 96 are provided which rest against springs 97 and 98, respectively, and tend to relieve the jar on the breaker mechanism.

The operating mechanism herein described, forms no part of my invention, except as it performs a necessary function in the operation of the device in question, and it may therefore be replaced by any other suitable means for accomplishing the same purpose.

The breaker being closed, and the various parts occupying the positions shown in the drawings, the operation is as follows: Assuming that the tripping magnet 90 is energized sufficiently to cause the hammer rod 92 of the movable core member 91 to engage the tripping lever 57 of the latch 73, the inner member 63 of the operating lever is released and the weight of the breaker parts, acting on the toggle formed by the connecting link 64 and the inner members 63 of the operating lever causes it to collapse, and the breaker opens. The operating lever member 63 then takes the position indicated by the dotted lines in Fig. 1, while the position of the operating handle 60 remains unchanged. The parts of the movable contact members are so proportioned that, in breaking the circuit, the current-carrying brushes are allowed to separate from the stationary contact terminals a considerable distance prior to the separation of the arcing tips and plates. The arc which is produced at the time of interruption is, therefore, restricted to the arcing tips and plates and the main contact surfaces remain in efficient condition to insure perfect contact. To set the breaker, the push button 82 is forced against the spring 80 and the locking trigger 83 is released by the rod 81. The operating handle 60 may then be raised to its uppermost position, where the latch 73 engages the inner member 63 of the operating lever, after which the breaker may be set by lowering the handle, until the locking trigger 83 again engages the catch 86 and thus retains the breaker in the closed position.

Whereas I have illustrated and described a specific circuit interrupter, I desire it to be understood that variations or modifications of the structure may be made which do not differ materially from the construction set forth, and I desire that only such limitations shall be imposed as are indicated in the appended claims.

I claim as my invention:

1. In a circuit interrupter, the combination with stationary contact members and movable contact members, of an operating mechanism therefor embodying a single supporting member and a plurality of yielding and adjustable means disposed above said supporting member for suspending said movable contact members therefrom and

thereby equalizing the pressure on the contact members.

2. A circuit interrupter comprising stationary contact terminals arranged in pairs, 5 movable bridging contact members, and an operating mechanism therefor embodying a supporting member, laterally disposed pairs of suspending rods and springs associated therewith for equalizing the pressure on the 10 contact surfaces of each bridging member.

3. A circuit interrupter comprising a plurality of stationary contact members arranged in pairs, a plurality of movable bridging contact members adapted to co- 15 operate therewith, an operating mechanism comprising a plurality of links, a single supporting member from which the bridging members are yieldingly suspended, and insulated pin connections about which the 20 bridging members are severally free to swing.

4. In a circuit interrupter, the combination with stationary and movable contact members, of an operating mechanism for 25 said movable contact members embodying a single supporting member for said movable contact members, two suspending rods for each of said movable contact members which extend through holes in the supporting member, and individual sustaining 30 springs for said rods which rest upon said supporting member.

5. In a circuit interrupter, the combination with stationary and movable contact

members, of an operating mechanism there- 35 for embodying a single supporting member; a plurality of laterally disposed rods pivotally connected to the movable contact members at one end, and resilient and adjustable means for suspending the said rods from the 40 said supporting member.

6. A circuit interrupter, comprising a plurality of stationary contact terminals arranged in pairs, a plurality of movable contact members yieldingly suspended from a 45 common supporting member and adapted to coöperate therewith, an operating mechanism for said supporting member and associated contact members and circuit terminals composed of a plurality of copper straps 50 secured in parallel grooves provided in the stationary contact terminals.

7. In a circuit interrupter, the combination with a plurality of pairs of stationary contact members, and a plurality of movable 55 contact members, of an operating mechanism for said movable members embodying suspending rods which are disposed in pairs laterally across each movable contact member, a supporting member for said rods and 60 springs surrounding said rods.

In testimony whereof, I have hereunto subscribed my name this 10th day of June, 1910.

FORD W. HARRIS.
